UNITED STATES PATENT OFFICE.

THOMAS C. MAXFIELD, OF NEW YORK, N. Y.

AIR-HEATER.

1,288,104.

Specification of Letters Patent. Patented Dec. 17, 1918.

Application filed February 26, 1915. Serial No. 10,832.

To all whom it may concern:

Be it known that I, THOMAS C. MAXFIELD, residing at and whose post-office address is 465 West 157th street, city of New York, in 5 the county of New York and State of New York, have invented certain new and useful Improvements in Air-Heaters; and I do hereby declare the following to be a full, clear, and exact description of the invention, 10 such as will enable others skilled in the art to which it appertains to make and use the same.

My invention relates to that type of air heaters in which the clear atmospheric air 15 is heated and supplied to the rooms of a house or other building.

The advantages of supplying pure heated air, instead of introducing into a room the products of combustion laden with coal gas, 20 are well understood, and heating systems in which pure air has been passed through pipes or tubes which intersect the line of travel of the products of combustion from the furnace to the chimney, have been suc- 25 cessfully adopted and used. They accomplish the heating by the single transfer of the heat units from the products of combustion to the air instead of having to create steam for the heating of the air.

30 The object of my invention is to improve the construction of air heaters of the character referred to, primarily with the object of enabling them to be made in small sizes for domestic use and at the same time in- 35 sure the effective heating of a quantity of air, relatively to the fuel consumed, which will substantially equal the amount of air heretofore heated by large constructions having extended heating surfaces. I also pro-

40 vide a substantially free and uninterrupted passage for the air so that the air, flowing without undue increase in velocity, may have full opportunity to absorb the heat from the products of combustion.

45 I also arrange the heating tubes so that they completely inclose the flowing column of air and I provide a novel arrangement of the tubes by which opportunity is afforded for them to give up practically all of their 50 heat to the air before reaching the chimney.

In the accompanying drawing, Figure 1 is a front elevation partly broken away. Fig. 2 is a partial section and elevation and Fig. 3 is a partial plan and section.

55 Referring to the drawing, I have shown a casing 1 inclosing the entire heater and

containing the furnace 2. Air ducts 3 are shown entering the casing 1, at or near its lower end. The air passes through the casing to flues 4 adapted to lead to the rooms 60 to be supplied with the heated air. The atmospheric air thus has a practically unrestricted passage through the casing 1.

I have shown the fire box 5 of the furnace 2 in connection with the chimney 6 by means 65 of a novel arrangement of tubes. From the top of the fire box extends a products of combustion flue 7 having outlet tubes 12 in communication therewith. These tubes are shown slanting upward from the flue 7 at 70 an angle of about 45 degrees and entering heads 9 vertically disposed within the casing 1 near the sides thereof.

Just above the inner ends of the series 75 of tubes 12 the flue 7 is shown formed with a baffle plate 10 which insures the passage of all of the gases through the tubes. Within the heads 9 the gases pass downward and enter a second series of tubes 8 which are disposed, relatively to the heads, sub- 80 stantially the same as the tubes 12 relatively to the flue 7. The gases pass upward through the tubes 8 and again enter the flue 7 above the baffle plate 10 and then out 85 through the chimney 6. The tubes 8 and 12 may, if desired, consist respectively of a single flue instead of a plurality of tubes as shown. Above the baffle plate 10 the flue is divided longitudinally by a central 90 wall 13.

At the lower portion of the heads 9, I have indicated clean out openings 14 which permit of readily emptying the heads of the soot that may fall therein and out of the flues 8. The soot collecting within the flues 95 12 falls back into the fire box.

I provide for shutting off some of the tubes while maintaining the passages through others. This is of advantage when in severe weather the wind may blow violently against one side of the house or other structure in which the furnace is installed. I have shown each of the tubes of the series 8 provided with a damper 15 at the point 100 of its intersection with the flue 7. These are shown mounted on rods 16 having handles 17 at the front and rear of the furnace. Each rod controls a predetermined number of tubes, that is, each rod may carry one or more dampers. In this way any desired 110 number of dampers may be closed regardless of the others and the heat is directed

through the portion most exposed to the weather. This purpose is also aided by dividing each of the heads 9 with a central transverse partition 18.

5 From the foregoing it will be seen that there is practically no restriction of the air draft from the inlets 3 to the conduits 4 and that the air draft is intersected twice by the flues 8 and 12, and that the greater 10 portion of the air, following the direct line to the conduits 4, will pass between the heads 9 and products of combustion flue 7, thus insuring the column of air being heated on all sides in addition to the heat units it 15 acquires from the flues 8, 12.

I claim as my invention:—

1. In an air heater, a casing having inlet and outlet ducts for the atmospheric air, a furnace within said casing, a products of 20 combustion flue leading from the fire box of said furnace, and having a baffle plate therein, a head at either side of said flue, an upwardly inclined tube leading from said flue below said baffle to the upper end of 25 said head, and a second upwardly inclined

tube leading from the lower end of said head to said flue above said baffle.

2. In an air heater, the combination with the casing having air inlets and outlets, of a furnace within said casing, a products of 30 combustion flue, vertically disposed from the fire box of said furnace and having a baffle plate therein, a head at either side of said flue, a pair of tubes leading from said flue beneath said baffle at an angle of substantially 45 degrees to near the tops of said heads, and a second pair of tubes leading from the lower portions of said heads to said flue above said baffle, and disposed at an angle of substantially 45 degrees, said flue, 40 heads and tubes being disposed in the passage of the air through said casing.

In testimony whereof, I have signed this specification in the presence of two subscribing witnesses.

THOS. C. MAXFIELD.
